UNITED STATES PATENT OFFICE.

THOMAS W. DEMAREST, OF PITTSBURGH, PENNSYLVANIA.

JOURNAL-BOX LUBRICATOR.

1,396,734.

Specification of Letters Patent.

Patented Nov. 15, 1921.

Application filed January 5, 1920. Serial No. 349,553.

To all whom it may concern:

Be it known that I, THOMAS W. DEMAREST, a citizen of the United States, and a resident of Pittsburgh, in the county of Allegheny and State of Pennsylvania, have invented certain new and useful Improvements in Journal-Box Lubricators, of which the following is a specification.

My invention relates in general to lubricators, and more particularly to pressure lubricators, and has special reference to the provision of an improved type of lubricator adapted for the automatic feeding of the lubricant to driving box journals or railway locomotives in order to insure the pressure of a continuous film of grease between the bearing surfaces of the axle and journal bearing resting upon it and thereby, as far as possible, minimize the occurrence of a hot-box and the frequent stoppages and interferences incidental thereto, and whereby not only may the life of the journal brass be greatly increased but the locomotive may be kept on the road for a longer period of time without lay-up in the shop for replacement of the journal brass, thus avoiding both the expense of new material and of labor incident to placing it in position, and also loss of the use of the locomotive.

Lubricators of the type referred to are designed particularly for feeding hard grease in cake form, rather than fluid oils, to locomotive driving box journals, and that general type in which my present invention finds perhaps its greatest field of utility includes a perforated or foraminous plate which bears marginally against the journal of the driving box and is adapted to distribute the grease and regulate the feed thereof to the axle, a follower-plate or riser, which supports the grease cake, and a spring acting on the follower-plate or riser to keep the grease cake in contact with the perforated plate, all contained within a casing or cellar. Means are provided by me for pulling down the follower-plate and distributor plate, whether for inspection of the condition of the lubricator or for replacement of the grease cake or parts worn away in service.

The principal objects of my present invention are generally to improve, simplify, and cheapen the cost of producing lubricators of the character referred to; to ren-

der such lubricators less complicated in structure and more efficient in operation, and less expensive in manufacture and in the cost of maintenance; the provision of the lubricator into which a fresh grease-cake may be introduced with the greatest facility; the provision of a lubricator in which the point of location in attachment of the sustaining spring to the containing cellar is above the riser-plate or cake-supporting follower when the latter is in its lower position in order to permit the insertion of a fresh cake and which is below such plate when the latter is in its upper position in which the cake is brought into action on the feed or distributor plate; the provision of a spring supporting device acting on the riser-plate at a number of points so that the plate is not only supported on the bottom but also is guided on its sides whereby any tendency toward cocking and consequent cramping in the casing is avoided; the provision of a bottomless container-cellular having continuous sides and ends adapted to contain the grease-cake and prevent on the one hand any lateral exudation thereof with consequent loss and on the other hand the entrance of any foreign matter; the provision of a riser-plate provided with raised longitudinal sides of sufficient depth to contain the grease-cake in such a manner as to prevent any seepage or loss of grease from the riser-plate except through the feed-plate and, of course, the ends of the riser-plate; the provision of an arrangement of a riser-plate and feed-plate so disposed that the latter may be drawn down with the riser-plate; the provision of a riser-plate arranged to interlock with the feed-plate for the same purpose; the provision of a riser-plate so arranged that it may be drawn down below the lower edges of the containing cellar for re-loading with a fresh cake of grease; the provision of a container-cellular provided with continuous ends and sides of sufficient depth, in combination with a feed-plate and riser-plate, to contain and cover the grease-cake on all sides while the lubricator device is in operative position; together with such other objects as may hereinafter appear.

In attaining the objects referred to, together with such additional benefits and advantages as may be below pointed out,

I have provided a construction, one embodiment of which is illustrated in the accompanying drawing wherein—

5 Figure 1 is a plan view of a lubricator embodying my present improvements;

Fig. 2 is a longitudinal sectional elevational view thereof taken on the line 2—2 of Fig. 1;

10 Fig. 3 is a transverse sectional elevational view thereof taken on the line 3—3 of Fig. 1; and

Fig. 4 is a perspective view of a conventional form of grease-cake, inserted in the device in the first instance.

15 On referring to the drawings, it will be observed that I have indicated a topless and bottomless cellar 10 provided with continuous ends and sides, 11 and 12, the ends 11 being marginally curved, as is perhaps most clearly to be seen on viewing Fig. 3, to conform to the contour of the axle 13.

20 Within the cellar is arranged a foraminous grease feed or distributor-plate 14, having a number of perforations 15, the plate 25 14 being also curved, as clearly to be seen on inspection of Fig. 3, to conform to the contour of the axle 13.

With the cellar 10 and surrounding the feed-plate 14 is a follower-plate or riser 16 30 which carries the grease-cake. This riser 16 has upturned sides 17 provided with inwardly turned marginal portions 18 adapted to contact with shoulders 19 formed on the downwardly turned sides 20^a of the feed-plate 14, as clearly to be seen on viewing the dotted portion of Fig. 3, in order that downward movement of the riser 16 may carry along the distributor 14.

For sustaining the riser or follower-plate 40 16, which carries the grease-cake 31, and for pressing it upward in order to force the grease-cake against the feed-plate 14 and thereby press the grease, as it becomes warmed, through the apertures 15 in the 45 plate 14 and so afford a continuous feed of grease to the axle 13, I employ a number of coiled spring devices 20, each of which is of a generally inverted U-form (see Fig. 3) and is provided at each end with a number 50 of coils 21 which are disposed in retaining sockets 22 formed in the walls 12 of the cellar 10.

The ends 23 of the springs are inserted in openings in the sides 12 of the cellar in 55 order to keep the springs under compression and thereby insure that the riser 16 is caused to approach the feed-plate 14, as closely as the body of the interposed grease-cake will permit.

60 In order to afford full support for the follower 16 at both ends thereof, the legs 24 of the spring device 20 are bent laterally and may be conveniently made integrally so as to continue the support of the riser 65 or follower entirely across its ends as indi-

cated at 25 (see Fig. 1) and afford a four-point support thereto, and prevent canting.

As further means for preventing any canting of the riser or follower 16, brackets 26, 26 are applied to the under side of the 70 riser or follower 16 and so arranged that the portions 25 of the spring device shall at all times be confined to movement within the length of such brackets.

For retracting the follower 16 from within 75 the cellar 10, that is withdrawing it therefrom and into the position at dotted lines in Fig. 3, for replacement of the grease-cake, a number of depending legs 27 (see Fig. 2) 80 apertured as indicated at 28 for the reception of hooks, (not shown), are conveniently employed.

Inasmuch as the retraction of the riser 16 eventually carries along with it the feed-plate 14, owing to the contact of the marginal extensions 18 with the shoulders 19, above referred to, it will be perceived that the distributor-plate 14 may be readily removed at any time for cleaning or replacement.

90 From inspection of Fig. 3, it will also be apparent that the construction described permits the retraction of the riser or follower 16 to a point sufficiently far below the lower margin 29 of the cellar 10 to permit the insertion of a fresh grease-cake between the lowermost point 30 of the feed-plate 14 and said riser 16, without any interference by the outer end 11 of the cellar 10.

95 As will be understood on viewing Fig. 3, 100 care should be used in assembling the device in order to keep the spring coils 21 well within the sockets 22 so that such coils may not interfere with either the upward or downward movement of the riser 16.

105 While I have shown in full lines in Fig. 4 a conventional form of grease-cake, 31, to be inserted in the device in assembling it in the first instance, it will be understood that the cakes of grease subsequently inserted 110 from time to time in replenishing the supply are of rectangular cross-section as indicated in dotted lines in such Fig. 4.

Having thus described my invention and illustrated its use, what I claim as new and 115 desire to secure by Letters Patent is—

1. A lubricating device comprising, in combination with a casing, of a distributor, a lubricant-supporting follower or riser, and a spring device arranged in said casing outside of the path of movement of said distributor and riser, and adapted to cause said riser to approach said distributor, the body of the spring device being below the riser when the riser is in its uppermost position, 112 and above the riser when the riser is in its lowermost position.

120 2. A lubricating device comprising, in combination with a casing, of a distributor, a lubricant-supporting follower or riser, and 125

- a spring device in said casing for causing said riser to approach said distributor, the spring device being so constructed and arranged in the casing as to permit the riser 5 to pass it in either direction without interference with its movement.
3. A lubricating device comprising, the combination with a casing, of a distributor, a lubricant-supporting follower or riser and 10 spring means acting in opposition to each other on both ends of said riser and adapted to cause it to approach said distributor.
4. A lubricating device comprising, the combination with a casing, of a distributor, 15 a lubricant-supporting follower or riser, and spring means acting in opposition to each other on opposite portions of said riser and adapted to cause it to approach said distributor.
- 20 5. A lubricating device comprising, the combination with a casing, of a distributor, a lubricant-supporting follower or riser, and spring devices acting on opposite portions of said riser at an angle to the plane thereof 25 and to each other and adapted to cause it to approach said distributor.
6. A lubricating device comprising, in combination, a casing, a distributor, a lubricant-supporting follower or riser, and a 30 spring device arranged in said casing for causing said riser to approach said distributor, said casing having continuous closed sides and ends with the top substantially closed by all so arranged that said riser may be 35 drawn through the open bottom of the casing for the insertion of a fresh supply of lubricant upon the top of said riser.
7. A lubricating device comprising, the combination with a casing, of a distributor, 40 a lubricant-supporting follower or riser, and a spring device arranged in said casing for causing said riser to approach said distributor, and means for limiting the maximum distance of separation between said 45 riser and distributor, the said riser having upwardly extending longitudinally arranged sides of a height greater than the maximum distance of separation between said riser and distributor whereby lateral displacement of 50 the lubricant carried by the riser is prevented.
8. A lubricating device comprising, the combination with a casing, of a distributor, a lubricant-supporting follower or riser, and 55 a spring device arranged in said casing adapted to cause said riser to approach said distributor, said riser and distributor being provided with means for inter-engagement whereby the distributor may be retracted 60 when the riser is retracted from said casing.
9. A lubricating device comprising, in combination, a casing, a distributor, a lubricant-supporting follower or riser, and a spring device arranged in said casing and adapted to cause said riser to approach said distributor, all so arranged that the riser may be retracted sufficiently far below the lower edge of the casing in order to permit the insertion of a fresh supply of lubricant. 65
10. A lubricating device comprising, in combination, a casing, a distributor, a lubricant-supporting follower or riser, a spring device arranged in said casing adapted to cause the riser to approach the distributor, 70 said casing having continuous closed sides and ends with the top substantially closed by said distributor and the bottom substantially closed by said riser but being of sufficient depth to contain a lubricant supply completely inclosed between the side and end 75 walls of the casing and said distributor and riser.
11. A lubricating device comprising, in combination, a casing, a distributor, a lubricant-supporting follower or riser, and a spring device arranged in said casing and adapted to cause said riser to approach said distributor, all so arranged that the riser and distributor may be retracted sufficiently far 80 below the lower edge of the casing in order to permit the insertion of a fresh supply of lubricant, between said riser and distributor. 85
12. A lubricating device comprising, in combination, a casing, a distributor, a lubricant-supporting follower or riser, and a spring device arranged in said casing and adapted to cause said riser to approach said distributor, all so arranged that the riser and distributor may be retracted sufficiently 90 far below the lower edge of the casing in order to permit the insertion of a hard grease-cake between said riser and distributor. 95
13. A lubricating device comprising in combination with a casing of a distributor, a lubricant supporting follower or riser, and means for causing said riser to approach said distributor, said means comprising an angularly movable member having a shiftable thrust engagement with said riser. 100
14. A lubricating device comprising in combination a casing, a lubricator supporting follower or riser, and means for causing said riser to move in one direction comprising an angularly movable member having free sliding and thrust engagement with 105 said riser. 115
- In testimony whereof I have hereunto signed my name.
- THOMAS W. DEMAREST.
